STENCIL

Frederic S. Tobey, Canton, Mass., assignor, by
mesne assignments, to W. H. Brady Co., Mil-
waukee, Wis., a corporation of Wisconsin

Application June 12, 1946, Serial No. 676,303

2 Claims. (Cl. 101—127)

1

This invention relates to a stencil sheet for use in the production of multi-colored designs, particularly letters and numerals as applied to airplanes, auto and truck bodies, and the like, for identification and advertising purposes. It is the primary object of the invention to provide such stencils which will enable multi-colored pin stripe designs to be quickly and accurately produced as by spraying and brushing with resultant savings in time, labor and material as compared with prior art practises and stencils.

In the accompanying drawings, illustrating a preferred embodiment of the invention:

Fig. 1 is a plan view showing the complete article of manufacture as sold in the trade, portions of the stencil sheet alone being turned up for purposes of better illustrating the construction;

Fig. 2 is a plan view and shows the main portion of the body sheet of the stencil in use, illustrating the same with one color partially applied to the larger opening therein;

Fig. 3 is a plan view, partly in perspective, showing the stencil with the principal portion of the opening being filled or covered by the replaced larger or central portion of the design, leaving a narrow pin stripe opening surrounding said portion as the pin stripe is removed therefrom as shown, and

Fig. 4 shows typical results of the use of the stencils of this invention in applying letters and a numeral to the vertical tail surface of an airplane.

Referring to the drawings in which like numerals represent like parts, the stencil embodies a body sheet 2 and a slip-sheet or backing sheet 4 temporarily secured thereto in face-to-face contact therewith by means of the body sheet 2 carrying a pressure-sensitive coating 6 for the temporary adhesive attachment of the two sheets in face-to-face relation. This adhesive coating is tacky and "everactive" so that it will not take a permanent set but provides a firm bond first to the backing sheet, and then to the base to which it is attached during actual use of the stencil. A typical satisfactory coating for this purpose may include ordinary rubber cement with rosin or synthetic resins added thereto with a suitable solvent for mixing and applying the same, to which may be added color or pigment as desired.

The body sheet itself is preferably made of high-tensile strength long-fibred paper and coated to sufficiently resist permeation by paint and lacquer solvents. After having been applied

10 to the backing sheet, the two sheets are together and simultaneously provided with through-and-through substantially continuous cut lines providing cut-outs defining letters, numerals and the like, said cut-outs being bordered by two uniformly-spaced narrow cut lines defining an inner portion 8 and pin stripe portion 10, for example, of the Arabic figure "3" as appears in the drawings wherein said lines are parallel since a block numeral is involved.

In typical use, the backing sheet 4 is carefully removed, at least from the outer portion of the stencil body sheet, which outer portion is then adhesively attached to a suitable base to which it is desired to apply the design, for example, as in Fig. 2, wherein the color 12 is shown as being applied to the base after removal of the outer and inner portions 8 and 10 which may be and preferably are removed as a unit.

Thereafter, following the drying of the color 12, and after removal of the portion of the backing sheet adherent thereto, unless previously removed, the outer and inner portions 8 and 10 are preferably together replaced as a unit in position overlying the color 12 and filling the entire space in the stencil. Thus, the central portion 8 is replaced in its original position and thereby necessarily uniformly spaced from the outer margin of the orifice by reason of the presence of the surrounding pin stripe portion 10.

35 The pin stripe portion may then be removed, leaving the central portion 8 pressed firmly in its desired properly spaced position, and a different color pin stripe 14 applied to overlie the margins of the color 12, thus providing, upon removal of the central portion 8, a pin stripe numeral "3" of uniform and precise width with the central portion of a different or contrasting color, as shown in Fig. 4. If desired, the stencil can also be employed simply to apply a pin stripe without a separate application of a central body portion by simply utilizing the background color of the base, and removing only the marginal portion of the pin stripe 10 of the stencil to provide pin stripe letters as shown by the letters "NC" 40 in Fig. 4.

45 It will, of course, be appreciated that the stencil of this invention is not limited in its use to the manner as above described, and that it also may be utilized in a different order of steps, and according to the effects it is desired to produce.

Having described my invention, I claim:

1. As a new article of manufacture, a flexible stencil for producing "pin stripe" designs, said 50 stencil comprising a backing sheet and a high

tensile strength body sheet, said body sheet having a pressure sensitive adhesive coating normally adherently holding it in face-to-face contact with said backing sheet, said coating being adapted to hold said body sheet to a base surface after said backing sheet is removed, and said body sheet also having outer and inner spaced cut lines defining a cut-out portion of a design to be applied to said base surface, said cut-out portion likewise having a cut line spaced inwardly from its edge dividing said cut-out portion into a central portion and a narrow "pin stripe" border portion separable therefrom, said central and border portions being adapted to be together or separately and selectively removed and replaced in their original positions in said body sheet in the use of the stencil.

2. An article according to claim 1 in which said backing sheet is provided with cut lines defining a cut-out portion having central and border portions in registry with the corresponding portions of said body sheet.

FREDERIC S. TOBEY.
